BOBBIN

William J. McGeough, Providence, R. I., assignor
to U S Bobbin & Shuttle Company, Manches-
ter, N. H., a corporation of Rhode Island

Application April 19, 1937, Serial No. 137,628

1 Claim. (Cl. 242—120)

This invention pertains to the art of weaving and relates more particularly to improvements in bobbins for use in loom shuttles, having particular reference to flat bobbins such as have recently come into commercial use, especially in weaving wiry and slippery yarns of artificial silk or the like,—the present application being a continuation-in-part of application Serial No. 116,334, filed December 17, 1936.

10 In addition to its ability to retain slippery and wiry yarns better than the usual round bobbin, a flat bobbin has certain other advantages, among them being that the yarn package wound on such a bobbin is more or less elliptical in cross section rather than circular, and that when placed in the shuttle with its longer transverse axis horizontal it occupies less space vertically for a given quantity of yarn, thus making it possible to use an abnormally low shuttle, an advantage of real importance from the standpoint of the weaver. However, in order that this latter advantage, among others, may be fully available, it is essential that the flat bobbin always be positioned in the shuttle with its longer transverse dimension substantially horizontal, and one of the objects of the present invention is to provide a bobbin designed for cooperation with a shuttle having bobbin-holding means, including a clutch device, operative definitely to hold the bobbin with its longer transverse axis horizontal.

25

30

It is always advantageous from the practical standpoint to place as much yarn as possible upon a bobbin, within the limits prescribed by the dimensions of the shuttle, in order to reduce the time lost in replenishment, and a further object of the invention is to provide a flat bobbin so designed as to permit a greater quantity of yarn to be placed on the bobbin than is usually possible when using a bobbin and shuttle of standard dimensions. Thus in accordance with one desirable embodiment, the present invention provides a bobbin of novel shape, in particular a flat bobbin having an abnormally short base or butt of small diameter designed to cooperate with holding means of usual type but disposed rearwardly of the usual bobbin chamber. To prevent the yarn from slipping rearwardly onto the butt or the bobbin, the bobbin is preferably provided with a shoulder at the junction of its body and butt portions.

In some weaving mills it is customary to weave yarns of both right and left twist, but care must be taken that yarn of one twist is not accidentally substituted for the other. To prevent such

accidental substitution of the wrong kind of yarn it is contemplated that two sets of bobbins and shuttles may be employed, each set being especially designed for use with right or left-hand twist yarn, respectively, the bobbin-holding means of a shuttle of one set being capable of holding corresponding bobbins but not bobbins designed for use in shuttles of the other set.

Other and further objects and advantages of the invention will be made apparent in the following more detailed description and by reference to the accompanying drawing, wherein

Fig. 1 is a plan view of a bobbin embodying certain features of the present invention, the bobbin being shown to small scale;

Fig. 2 is an edge elevation of the bobbin of Fig. 1;

Fig. 3 is a transverse section on the line 3—3 of Fig. 2, but to larger scale;

Fig. 4 is an end elevation of the butt end of the bobbin to larger scale;

Fig. 4^a is a view similar to Fig. 4, but showing an alternative arrangement;

Fig. 5 is a fragmentary diametrical section substantially on the line 5—5 of Fig. 4, but to larger scale; and

Fig. 6 is a fragmentary vertical section through a shuttle showing bobbin-holding means designed for cooperation with the bobbin shown in Figs. 1 to 5, the bobbin-receiving spindle being broken off and turned up to bobbin-receiving position.

Referring to Figs. 1 to 5 of the drawing, the numeral 1 designates the bobbin generally, such bobbin having the body or blade portion 2 and a butt portion 3. Preferably, in accordance with the present invention, the butt portion 3 is abnormally short, as compared with the butt portions of standard bobbins. In accordance with a preferred construction, the overall length L of the bobbin should be at least twelve times the length of the butt, and preferably more. The body portion 2 is of elongate wedge shape, tapering from its junction with the butt toward its other end and having substantially flat upper and lower surfaces 4 and 5, respectively, which converge toward the tip of the bobbin and the relatively narrow lateral edges 6 and 7. The flat surfaces 4 and 5 of the bobbin are preferably of substantially uniform width from end to end except near the tip 7^x where they may abruptly taper, as shown at 8, so as to form a more or less pointed end. As indicated in Fig. 3, any transverse section of the body of the bobbin is of generally rectangular contour, although the

edges 6 and 7 are preferably somewhat curved or arcuate.

The butt 3 is preferably of circular transverse section and of a diameter not substantially greater and preferably somewhat less than the maximum width of the flat surfaces 4 and 5 of the bobbin body, but is always of a diameter greater than the maximum width of the lateral edge surfaces 6 or 7. A butt so dimensioned is of particular value when it is desired to support the bobbin by means of bobbin-holding jaws disposed nearer to the end of the shuttle than is customary, thereby to save as much of the bobbin chamber as possible for the reception of yarn. 15 The abnormally short length of the bobbin butt is also conducive to the same mode of mounting the bobbin in the shuttle.

The bobbin is provided with a bore 9 extending forwardly from its butt end to a distance sufficient to accommodate the usual spindle by means of which the bobbin is positioned within the shuttle, it being noted, however, that by reason of the tapering or wedge-shape form of the bobbin it is not possible to extend this bore 25 to as great a distance from the butt end as is common in bobbins of the usual type. Preferably in accordance with the present invention this bore is purposely made of a diameter somewhat larger than that of the shuttle spindle with 30 which it is to be used, so that the bobbin may be properly centered within the shuttle body even though the spindle itself may be slightly out of line.

The rear end surface of the butt of the bobbin, 35 as illustrated in Fig. 4, for example, is furnished with a slot 10 substantially parallel to the shorter transverse axis of the bobbin body, such slot constituting one element of a clutch device designed to prevent the bobbin from turning on the shuttle spindle when the bobbin is disposed within the bobbin chamber.

If it be desired to provide bobbins for use with right and left-hand twist yarn, certain of the bobbins may be furnished with slots 10 which, as 45 shown in Fig. 4, are parallel to the shorter transverse dimension of the bobbin body, while others, as illustrated for example in Fig. 4^a, have their slots 10^a disposed parallel to the longer transverse axis of the bobbin body. Thus by the use of 50 proper cooperating clutch elements in shuttles of two distinct types, it is only possible to mount a bobbin having right-hand twist yarns, for example, in operative position in the shuttle designed to hold bobbins carrying yarn of this 55 twist.

Preferably a yarn retaining shoulder 12, extending peripherally of each of the narrow edge faces 6 and 7, is provided at the junction of the bobbin body with the butt, so as to prevent yarn 60 wound on the body portion from slipping rearwardly onto the butt portion where it might interfere with the bobbin-holding elements, it being noted that since the diameter of the butt portion is greater than the maximum width of the narrow edge surface 6 or 7, there is also 65 formed a shoulder 12^a (Fig. 2) at the butt end of each of said surfaces 4 and 5.

As illustrated in Figs. 1, 2, 4 and 5, the butt 3 is provided with two peripheral ribs 11, consisting, for example, of split resilient steel rings set 70 into grooves in the material of the butt. In accordance with the present invention but two of these rings or ribs are provided, whereas it has been common, heretofore to provide the bobbin butt with three or more rings for cooperation with

complemental recesses in the bobbin-holding jaws of the shuttle. It has been found that better results are obtainable by using two rings and a corresponding pair of recesses than by using three or more, since as a practical matter 5 it is difficult to set or maintain three or more rings so that one will not be a little higher than the others and tend to cant the bobbin out of alignment, whereas when but two rings are employed it is possible as a practical matter to 10 obtain accurate results and to hold the bobbin in proper alignment with the axis of the shuttle.

In Fig. 6 an end portion of a shuttle 13 is diametrically indicated, such shuttle having a narrow chamber 14 constituting an extension of 15 the usual bobbin chamber. This narrow chamber 14 houses usual resilient bobbin-gripping jaws 15 each provided with two recesses 16 for cooperation with the rings 11 of the bobbin. A bobbin-positioning spindle 17 is also shown, such 20 spindle having a butt portion 18 which is disposed between the jaw members 15 and which is pivotally mounted on a transverse pin 19. The spindle 17 is furnished with a clutch element, for example a horizontally projecting pin 20 25 designed to cooperate with a slot arranged like the slot 10^a of the bobbin of Fig. 4^a, thus to hold the bobbin definitely in position with its longer transverse dimension horizontal. Obviously, by placing the pin 20 or its equivalent so as to lie in a vertical 30 plane, it will cooperate with a slot or recess such as that shown in Fig. 4, so as to hold the bobbin with its longer transverse axis horizontal.

In placing the bobbin in the shuttle, the spindle 17 is swung up to the position illustrated in 35 Fig. 2, and the bobbin is slipped freely onto the spindle and pushed rearwardly and turned until the slot or recess in its butt can be fitted over the pin 20. When the bobbin has thus been seated on the spindle the latter is then swung 40 down onto the shuttle body and as it nears the horizontal position the rings 11 are accurately guided to enter the recesses 16 of the resilient gripper jaws, thus effectively holding the bobbin in alignment in the shuttle regardless of any 45 slight inaccuracy of the spindle 17. Moreover, when once disposed in the bobbin chamber, the clutch elements, including the recess in the bobbin butt and the pin 20 or its equivalent, prevent any turning of the bobbin relatively to the spindle so that its proper position within the bobbin 50 chamber is assured.

Since the butt of the bobbin is abnormally short and of small diameter it is possible to locate it within the narrow chamber 14 in the end of 55 the shuttle body and thus keep the entire length of the bobbin chamber for the accommodation of the yarn-carrying portion of the bobbin. It thus becomes possible to place a greater quantity of yarn, for example 10% more on the bobbin 60 than is usually permissible for a bobbin of given dimensions, and thus the time consumed in replenishment is substantially reduced.

While certain desirable embodiments of the invention have been illustrated by way of example, 65 it is to be understood that the invention is not necessarily limited to these precise constructions, but is to be regarded as broadly inclusive of any equivalent arrangements such as fall within the scope of the appended claim.

I claim:

A bobbin for use in loom shuttles, said bobbin being of the kind which has a substantially cylindrical butt portion and an elongate, substantial 70 wedge-shaped body portion directly and in- 75

tegrally united to the butt portion, the body portion being of substantially rectangular transverse section, those faces of the body portion which, in use, are the top and bottom faces being substantially flat and of substantially uniform width except adjacent to the tip, the edge faces being relatively narrow as compared with the top and bottom faces and tapering with a smooth, substantially unbroken taper from their butt ends to the tip, the bobbin having an axial bore extending from its butt end toward its tip for the reception of a shuttle spindle, and a pair of longitudinally spaced shuttle-jaw engaging rings embracing the butt portion, the butt portion being

of a length sufficient to accommodate but two such rings, characterized in that the butt portion is of a diameter greater than the maximum vertical thickness of the body portion and less than the maximum horizontal thickness of the body portion and in that the butt portion has a substantially flat surface substantially parallel to the diameter of the butt portion for engagement by a bobbin-positioning element of a shuttle, thereby to hold the bobbin positively with its longer transverse axis horizontal when in use. 5

WILLIAM J. McGEOUGH.
